Primary Examiner—Alan P. Douglas*Assistant Examiner*—S. Snapp*Attorney, Agent, or Firm*—Michael Sand Co.[57] **CLAIM**

The ornamental design for an insert for video cassette package, as shown and described.

DESCRIPTION

FIG. 1 is a perspective view of an insert for video cassette package;

FIG. 2 is a top plan view thereof;

FIG. 3 is a right side elevational view of FIG. 2, the left side being the same;

FIG. 4 is a side elevational view of FIG. 2, the opposite side being the same;

FIG. 5 is a bottom plan view thereof;

FIG. 6 is a perspective view similar to FIG. 1 of a modified insert for a video cassette package; and,

FIG. 7 is a bottom plan view of FIG. 6.

FIG. 1

FIG. 2

FIG. 3

FIG. 4

FIG. 5

FIG. 6

FIG. 7
